UNITED STATES PATENT OFFICE.

JOHN HENRY ZEILIN, OF PHILADELPHIA, PENNSYLVANIA.

DESIGN FOR A CLOCK-CASE.

SPECIFICATION forming part of Design No. 22,783, dated September 12, 1893.

Application filed April 14, 1893. Serial No. 470,383. Term of patent 3½ years.

To all whom it may concern:

Be it known that I, JOHN HENRY ZEILIN, a citizen of the United States, residing at Philadelphia, in the county of Philadelphia and State of Pennsylvania, have invented and produced a new and original Design for Clock-Cases, of which the following is a specification, reference being had to the accompanying drawing.

The leading feature of my design is an outline of a ship, the ship's hull and bulwark, and sails being patterned after the ship *Santa Maria*, the ship in which history tells us Columbus set sail on his voyage of discovery to

America. The ship is fitted with three masts: A main-mast; a fore-mast; a mizzen-mast. On the fore-mast is the fore-course sail set full; on the main-mast is the main-course sail

set full, also the main top-sail set full, and at the top of the main-mast is a flag or pennant 20 spread out; on the mizzen-mast is the mizzen-course sail set full. In the center of the main-course sail appears the dial of a clock with hands.

What I claim is—

The design for clock cases herein shown and described, the same comprising the outline of a Columbus caravel ship with three masts, with sails set on each mast, and in the center of the main-course sail the dial of a 30 clock.

JOHN HENRY ZEILIN.
